US0D1108656S

(12) **United States Design Patent** (10) **Patent No.:** **US D1,108,656 S**
(45) **Date of Patent:** **** Jan. 6, 2026**

(54) **SAMPLE HANDLING DEVICE**

(71) Applicant: **10x Genomics, Inc.**, Pleasanton, CA (US)

(72) Inventors: **Pratomo Putra Alimsijah**, Pleasanton, CA (US); **Hendricus Marindra**, Pleasanton, CA (US); **Augusto Manuel Tentori**, Dublin, CA (US); **Spontaneous Rose McKnight Russell**, San Ramon, CA (US); **Hanyoup Kim**, Foster City, CA (US); **Colin Bruce Kennedy**, Greenbrae, CA (US)

(73) Assignee: **10x Genomics, Inc.**, Pleasanton, CA (US)

(**) Term: **15 Years**

(21) Appl. No.: **29/953,635**

(22) Filed: **Jul. 23, 2024**

Related U.S. Application Data

(62) Division of application No. 29/808,262, filed on Sep. 17, 2021, now Pat. No. Des. 1,064,308.

(57) **CLAIM**

The ornamental design for a sample handling device, as shown and described.

DESCRIPTION

FIG. 1 is a front, top, and right side isometric view of a sample handling device showing our new design;

FIG. 2 is a rear, bottom, and left side view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The dash-dash broken lines illustrate portions of the sample handling device that form no part of the claimed design.
